(74) *Attorney, Agent, or Firm* — Young & Thompson

(57) **CLAIM**

The ornamental design for an arithmetic and control unit, as shown and described.

DESCRIPTION

FIG. 1 is a perspective view of front, top and right side of an arithmetic and control unit showing my new design; FIG. 2 is a perspective view of rear, bottom and right side thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a cross sectional view taken along line 9-9 of FIG. 3;

FIG. 10 is a cross sectional view taken along line 10-10 of FIG. 3; and,

FIG. 11 is an enlarged view of the area 11 of FIG. 3. The broken lines form no part of the claimed design.

1 Claim, 9 Drawing Sheets
